(57) **CLAIM**

The ornamental design for the wheel, as shown and described.

DESCRIPTION

FIG. 1 is a front perspective view of a wheel, showing my new design; and,

FIG. 2 is a front view showing the wheel of FIG. 1. In the drawings, the broken lines depict environmental subject matter and form no part of the claimed design.

1 Claim, 2 Drawing Sheets*FIG. 1*

FIG. 2
